THOMAS J. FAY, OF CLEVELAND, OHIO, ASSIGNOR, BY MESNE ASSIGNMENTS, TO THE STANDARD PARTS COMPANY, OF CLEVELAND, OHIO, A CORPORATION OF OHIO.

INTERNAL-COMBUSTION ENGINE.

1,267,529.

Specification of Letters Patent.

Patented May 28, 1918.

Application filed May 6, 1914. Serial No. 836,634.

To all whom it may concern:

Be it known that I, THOMAS J. FAY, a citizen of the United States, residing at Cleveland, in the county of Cuyahoga and State of Ohio, have invented a certain new and useful Improvement in Internal-Combustion Engines, of which the following is a full, clear, and exact description, reference being had to the accompanying drawings.

10 This invention relates to valve mechanism for internal combustion engines and more particularly to a construction and method whereby such mechanism may be efficiently cooled. More limitedly, the invention relates to a construction and arrangement of parts whereby, in a valve mechanism comprising an open-ended sleeve which is reciprocably mounted on a hollow piston or abutment, effective means are provided

15 whereby the said hollow piston or abutment, as well as the contacting valve, may be cooled through the circulation of liquid through the abutment and the temperature of the incoming and outgoing gases may be efficiently regulated. With the foregoing objects in view, the invention may be further and more generally defined as consisting of the combinations of elements set forth in the claims hereto annexed and illustrated

20 in the drawings accompanying and forming part hereof, wherein Figure 1 represents a sectional view through a valve mechanism constructed in accordance with my invention showing the same in connection with the adjacent part of the cylinder; Fig. 2 represents a similar view illustrating a modification of the invention shown in Fig. 1.

Describing by reference characters the various parts illustrated herein, 1 denotes the cylinder of an internal combustion engine and 2 the water jacket usually provided therefor and surrounding the upper end of the same. The valve mechanism coöperating with the cylinder is of the general type shown and described in the application of Clifford S. Goby No. 514,098, filed August 23, 1909, and comprises generally a cylindrical valve casing 3 having a port registering with the port 4 extending from the cylinder head. The valve casing 3 is preferably cast with the water jacket casing which surrounds the upper end of the cylinder and

has at its upper end an annular shoulder 5 extending at right angles therefrom, which shoulder is connected by a cylindrical wall 6 with the top of the water jacket casting and, as stated before, is preferably part of such casting.

As is the case with the construction shown in the aforesaid Goby application, it is preferred to use two valves in connection with the cylinder, namely; an inlet valve and an exhaust valve. As the valves are substantially identical in construction, it will be necessary to show but one such valve, and the exhaust valve is the one chosen for purposes of illustration. The cylindrical portion 6 is provided with a port 7 by which it communicates freely with the water jacket 2. 8 denotes a sliding sleeve reciprocably mounted within the casing 3 and operated by means of a connecting rod 9, in the ordinary manner. This sleeve is provided with ports 10 which are adapted to register with the passageway 4 whereby, in the case of an exhaust valve, the exhaust gases may escape through the ports and pass upwardly and outwardly through the port 11 extending through the water jacket and, in the case of an inlet valve, the combustible fluids may enter the passageway 4, the port 11 then serving as an inlet port.

12 denotes a hollow piston or abutment which fits the inner wall of the sleeve 8 and which is located immediately below the passageway 4. This piston or abutment is suspended from the shoulder or seat 5 through a reduced intermediate neck 13 which is provided at its top with an outwardly projecting shouldered flange 14 by which the abutment is suspended and a passageway for the fluids is provided between the reduced neck portion 13 and the valve sleeve 8 and the casing 3.

It will be observed that the piston or abutment 12 is closed at the bottom, and the abutment assembly is open from the bottom throughout its length, whereby its upper end communicates freely with a chamber 6^a provided within the cylindrical wall 6.

15 denotes a cover for the chamber 6, which cover has rigidly secured thereto a stand pipe 16, which stand pipe projects downwardly and centrally with respect to

the abutment neck 13, the lower end of this stand pipe projecting substantially as far as the bottom of the hollow abutment.

In the operation of the engine (assuming the valve heretofore described to be an exhaust valve) the exhaust gases pass through the port 4 and the port or ports 10, whence they are directed through the upper end of the reciprocating sleeve 8 and through the valve casing to the exhaust port 11, giving up their heat to the cooling solution or liquid; in the case of an inlet valve, the entering combustible fluids follow the reverse course and are heated by the cooling solution or liquid. The stand pipe 16 delivers relatively cold solution or liquid to the abutment or piston chamber below the port 4 and the heating of this liquid by the exhaust gases causes the cooling liquid to circulate so that it rises through the narrow neck portion 13 and is delivered through the port 7 into the valve and cylinder water jackets, the construction affording a relatively large surface to be heated in proportion to the volume of cooling solution or liquid necessary to fill the reduced neck portion 13.

In Fig. 2 there is shown a construction which is substantially identical with that shown in connection with Fig. 1, the elements from 1 to 14 being in fact identical and being designated by like reference characters. In this modification, however, the cap 17 does not carry a stand pipe, but liquid is positively circulated through the abutment 35 and the valve and cylinder water jackets by means of a pipe 18 to which any suitable liquid circulating device is connected. In this case the pipe 18 is connected to the bottom 19 of the abutment 12.

By the construction illustrated and described herein, the cooling liquid may be circulated throughout the abutment and the neck connected thereto while the fluids passing to and from the engine cylinder are separated and isolated from the crank casing and are directed in their course to or from the engine cylinder, according as the valve is an inlet or an exhaust valve.

Reference has been made hereinbefore to the "water jacket" of the cylinder and valve mechanism. By this expression I do not mean to imply that the cooling liquid shall be simply water. On the contrary, I contemplate employing a cooling liquid that will not boil at the ordinary boiling point of water nor at the ordinary working temperature of internal combustion engine. For such a fluid, I may use oil of specific gravity 9.9. By using such a cooling liquid, its temperature may be maintained substantially uniform throughout, thereby largely preventing local differences of temperature in such liquid.

In both constructions illustrated herein, the enlarged or valve-fitting portion of the

abutment extends downwardly from the port 4 so as to provide a maximum length for such enlarged portion whereby a maximum cooling of the inner surface of the valve is provided. Also, in both forms of construction shown herein, the port 11 is located above the port 4, whereby in the case of an exhaust valve, the heated gases are caused to pass between the valve 8 and the neck 13 so that the said gases will be efficiently cooled in their passage to the port 11. In the case of an inlet valve, the incoming gases are warmed by their passage through the space between the valve 8 and the neck 13.

Having thus described my invention, what I claim is:

1. The combination, with an engine cylinder and a cooling-liquid jacket therefor, of a cylindrical valve casing within the jacket and having a port communicating with the upper end of the cylinder, a reciprocating valve sleeve within the casing, a hollow elongated abutment within the valve casing and forming with the casing an annular guide for the sleeve, said abutment having an upper reduced extension providing clearance with the valve sleeve, there being a fluid port communicating with the interior of the valve casing at a point above the cylinder port, the abutment extension projecting beyond such fluid port and communicating with the jacket space, and a liquid supply pipe connected to the bottom of said abutment and by means of which liquid is positively circulated through the elongated abutment, the extension thereof and the jacket space.

2. The combination, with an engine cylinder and a cooling-liquid jacket therefor, of a cylindrical valve casing within the jacket and having a port communicating with the upper end of the cylinder, a reciprocating valve sleeve within the casing and having a port intermediate of the ends thereof, a hollow abutment within the valve casing and having an enlarged lower end extending downwardly from the cylinder port and provided with a reduced extension projecting upwardly from such enlarged lower end and communicating at its upper end with the jacket space, the valve casing being provided with a port above such lower end of the abutment, and a liquid supply pipe arranged to discharge into the hollow abutment adjacent to the bottom thereof.

3. The combination, with an engine cylinder and a cooling-liquid jacket therefor, of a cylindrical valve casing within the jacket and having a port communicating with the upper end of the cylinder, a reciprocating valve sleeve within the casing and having a port intermediate of the ends thereof, a hollow abutment within the valve casing and having an enlarged lower end

extending downwardly from the cylinder port and provided with a reduced extension projecting upwardly from such enlarged lower end and communicating at its upper 5 end with the jacket space, the valve casing being provided with a port above such lower end of the abutment, and a liquid supply pipe connected to the bottom of said abutment and by means of which liquid is posi-

tively circulated through the elongated abut- 10 ment, the extension thereof and the jacket space.

In testimony whereof, I hereunto affix my signature in the presence of two witnesses.

THOS. J. FAY.
